FIG. 3.

Pompeo Pieri, ^{INVENTOR}

BY Richard R.

ATTORNEYS

UNITED STATES PATENT OFFICE.

POMPEO PIERI, OF PARIS, FRANCE.

PADDLE-WHEEL.

SPECIFICATION forming part of Letters Patent No. 623,424, dated April 18, 1899.

Application filed October 15, 1898. Serial No. 693,678. (No model.)

To all whom it may concern:

Be it known that I, POMPEO PIERI, a subject of the King of Italy, permanently residing at Paris, France, and temporarily residing in the 5 city, county, and State of New York, have invented certain new and useful Improvements in Paddle-Wheels, of which the following is a full, clear, and exact specification.

My invention relates to paddle-wheels for 10 steamboats and the like; and the object of the invention is to provide a paddle-wheel that is less liable to be damaged than the ordinary paddle-wheel and will when in motion increase the speed of the boat to which it is 15 secured.

My invention relates also to the particular arrangement of my improved paddle-wheel, to be hereinafter fully described.

In constructing the paddle-wheel I make 20 that portion to which the paddle-wheel blades are fastened of large diameter in order that strength of action upon the water may be obtained. I provide three sets of paddle-wheel blades, consisting of six blades, and arrange 25 them alternately on both sides of the wheel. The blades on the inner side are spoon or oar shaped, while the blades on the outside of the wheel are so formed that they will incline to the center of the paddle-wheel. By 30 this construction I am enabled to cause a saving of fuel in that a lesser power is required to drive the paddle-wheel than is required with the ordinary wheel. The object of inclining the outer paddle-wheel blades is to 35 have them take up and throw aside the water cast up by the blades on the inner side of the wheel.

It has also been the usual practice heretofore to provide ships with paddle-wheels at 40 their stern; but in my construction I provide a set of paddle-wheels at each side of both the stern and the prow, which receive their power from the engine in the usual manner.

Referring to the drawings forming part of 45 this application, in which similar letters of reference indicate similar parts throughout, Figure 1 represents a portion of a ship provided with my improved paddle-wheels. Fig.

2 represents the paddle-wheel; and Fig. 3 is a sectional view of the paddle-wheel, taken on 50 line 4 4 of Fig. 2.

In securing the inner and outer paddle-wheel blades A and X, respectively, to the wheel B any desired or suitable means may be employed. It is usual to use ordinary bolts 55 or studs with nuts at the ends to prevent them slipping out. In the drawings I have shown the studs at a.

The paddle-wheels at the stern are secured to a common axis at D, about which they 60 revolve and at such distance from the body of the ship as to prevent the blades from coming into contact therewith. At the prow of the ship the paddle-wheel blades are similarly secured to a common axis, about which they 65 revolve; but the entire paddle-wheel is secured to the body of the ship proper by means of the axis, which penetrates and runs entirely through the prow. The paddle-wheels at both stern and prow may be driven by an 70 engine situated at or about the center of the ship, furnishing power to them, or a separate power-engine may be employed for each paddle-wheel, or I may use any other motive power giving the desired result. 75

I may of course use any number of paddle-wheels of any suitable size arranged at any desired plan; but I prefer to arrange them as above described, at the prow and at the stern.

The blades have a straight leading edge 80 extending radially or substantially so, while the rear edges of the blades are curved, and the rear portions of the blades are curved to the front, forming spoon-like or concaved surfaces. By reason of the spoon-like or concaved surfaces the front blade of each pair will throw or turn the water laterally into the path of the spoon-like or concaved surface on the second blade of this pair. The propeller may be used as a paddle-wheel, in which case 85 the upper part thereof would be out of the water and the straight edge would be the leading edge, which would cut the water when it reaches a horizontal position, or the line 4 4 in Fig. 2. 90

Having described my invention, what I 95

claim, and desire to secure by Letters Patent, is—

In combination in a paddle-wheel, the two blades, one being arranged in rear of the other, 5 both blades having straight leading edges and curved rear edges with the concave or spoon-like face, said concaved surfaces being formed by bending the rear curved and upper parts of the blades laterally, both blades being simi-

larly bent with their concave faces on the same side substantially as described.

In witness whereof I have hereunto set my hand in presence of two witnesses.

POMPEO PIERI.
